UNITED STATES PATENT OFFICE.

THOMAS BILYEU, OF PORTLAND, OREGON, ASSIGNOR TO UNITED STATES CASHIER COMPANY, OF PORTLAND, OREGON, A CORPORATION.

DESIGN FOR A CASING FOR COIN-HANDLING MACHINES.

43,401.

Specification for Design.

Patented Dec. 31, 1912.

Application filed July 16, 1912. Serial No. 709,824. Term of patent 14 years.

To all whom it may concern:

Be it known that I, THOMAS BILYEU, a citizen of the United States, residing at Portland, in the county of Multnomah and State of Oregon, have invented a new, original, and ornamental Design for Casings for Coin-Handling Machines, of which the following is a specification, reference being had to the accompanying drawings, forming a part thereof, in which—

The figure is a perspective view of a casing for a coin handling machine, showing my design.

I claim:

The ornamental design for a casing for a coin handling machine, as shown.

THOMAS BILYEU.
